APPARATUS FOR OPERATING METALLURGICAL FURNACES

Julius H. Strassburger, Steubenville, Ohio, assignor to National Steel Corporation, a corporation of Delaware

Filed June 5, 1958, Ser. No. 740,052

15 Claims. (Cl. 266—30)

This invention relates to blast furnaces and more particularly to apparatus for controlling the composition of blast gas for such furnaces.

It is known that improved performance may be obtained from blast furnace installations by enriching blast gas with oxygen or by introducing blast gas at elevated temperatures into the furnace, providing sufficient moisture is added to the blast gas to insure smooth furnace operation. The quantity of moisture required in blast gas in order to maintain a smooth operating furnace blown with oxygen enriched blast gas or blast gas at an elevated temperature depends upon the percent of oxygen enrichment and the temperature of the blast gas, the quantity of necessary moisture being greater as the oxygen enrichment or the blast temperature increase. In the copending application of Julius H. Strassburger, Serial No. 736,468 filed May 20, 1958, for "Method of Operating Metallurgical Furnaces" there is disclosed the quantity of moisture required for different percentages of oxygen enrichment and for different blast gas temperatures. In particular, with a blast gas temperature of about 1100° F. the required moisture may vary from about 3 grains to about 40 grains per cubic foot of blast gas as the oxygen enrichment varies from 1% to 10%, while with blast gas at a temperature of 1200° F. to 2500° F. and containing from 1% to 10% oxygen enrichment the required moisture may be as low as about 7.3 grains per cubic foot of blast gas and as high as about 82.2 grains per cubic foot of blast gas.

Blast furnace installations ordinarily include a number of steam driven prime movers and accordingly a large quantity of exhaust steam at substantially atmospheric pressure is available as an inexpensive source of aqueous fluid for providing the required blast gas moisture. The low pressure exhaust steam may be mixed with atmospheric air fed to the suction side of a compressor for blowing blast gas through the tuyeres and into the furnace. Since the quantity of moisture that may be added to blast gas on the suction side of the compressor is limited, for the most part, by the existing temperature, it is not possible to meet the moisture requirements by the use of low pressure steam except when the blast gas is blown to the furnace at relatively low temperature and contains low percentages of oxygen enrichment. High moisture requirements have been satisfied in the past by introducing high pressure steam to blast gas on the discharge side of the compressor. Steam under a sufficiently high pressure for this purpose is not available in blast furnace installations as "waste" steam and the power required to provide an adequate source of high pressure steam constitutes a material expense item in view of the large volume of moisture blown into the furnace during each twenty-four hour operating period.

The present invention provides a novel apparatus by which the required moisture content of blast gas is obtained in such a manner as to utilize at all times the maximum possible quantity of low pressure steam irrespective of the temperature and natural moisture content

2

of atmospheric air. This is accomplished by the provision of means for adding low pressure steam to blast gas on the suction side of the compressor and for adding high pressure steam to blast gas on the discharge side of the compressor, and the provision of a novel control apparatus which functions to maintain a predetermined quantity of moisture in blast gas blown to the furnace irrespective of variations in natural moisture content of the atmospheric air while at the same time insuring that the maximum possible quantity of the moisture in the blast gas is supplied from the source of inexpensive, low pressure steam.

The foregoing and other objects and features of the present invention will appear more fully from the following detailed description considered in connection with the accompanying drawings which disclose several embodiments of the invention. It is to be expressly understood, however, that the drawings are designed for purposes of illustration only and not as a definition of the limits of the invention, reference for the latter purpose being had to the appended claims.

In the drawings, in which similar reference characters denote similar elements throughout the several views:

Figure 1 is a diagrammatic view illustrating a blast furnace installation embodying the principles of the present invention;

Figure 2 is a diagrammatic view illustrating a blast furnace installation constructed in accordance with another embodiment of the present invention, and

Figure 3 is a diagrammatic showing of a blast furnace installation including a further embodiment of the present invention.

With reference more particularly to Figure 1 of the drawings, a blast furnace installation constructed in accordance with the principles of the present invention is disclosed therein including a blast furnace 10 having a vertical substantially cylindrical stack 11 provided with a large bell 12 and a small bell 13 for facilitating the charging of solid burden into the top of the furnace. At the top of the stack 11 one or more takeoff pipes 14 are provided for conducting top gas from the top of the furnace. The stack is supported at its lower end by a plurality of pillars 16 arranged around the lower periphery of the furnace. At the lower end of the furnace there is a hearth 17 supported by base 18, and between the hearth and the stack a bosh 20 is provided. A bustle pipe 22 encircles the lower portion of the furnace for supplying blast gas under pressure to the hearth. A plurality of tuyeres 23 are positioned around the upper portion of the hearth and project through the walls defining the hearth. The tuyeres 23 are connected by blow pipes 24 to the bustle pipe 22 so that compressed blast gas fed to the bustle pipe flows through the blow pipes and then through the tuyeres and into the furnace hearth. Molten slag and iron collects in the hearth and a tap hole 27 is provided for periodically tapping molten slag from the furnace. An iron notch 28 is provided in the hearth at a level below the tap hole 27 through which molten pig iron is periodically removed from the furnace.

Compressor means, such as a blower 30 is provided for compressing blast gas for the furnace. The blower 30 may be driven by a steam engine or an electric motor 32 connected to the blower through a shaft 33. Blast gas discharged from the blower 30 is conducted by conduit 34 to suitable stove means, not shown, for preheating the blast gas. The stove means may be of conventional construction including a plurality of individual stoves that are heated by burning top gas from the furnace and then used to preheat the blast gas, and a by-pass pipe may be provided for controlling the blast gas temperature. Heated blast gas from the stove means is conducted

through conduit 35 to the bustle pipe 22 for distribution to the tuyeres. The suction side 36 of the blower 30 is connected to one end 37 of a conduit 38 which communicates at its other end 39 with a source of blast gas such as atmospheric air. A filter 40 mounted in a casing 41 may be provided in the conduit 38 adjacent its end 39 to remove dirt and dust from the entering air.

Apparatus for maintaining at a predetermined value the quantity of blast gas flowing through the compressor 30 includes a venturi type measuring device 42 mounted in the conduit 38 and a blower control 43 connected to the venturi measuring device through loading lines 44 and 45. The venturi measuring device may be of conventional construction and may include a compensator 46 connected to the loading lines 44 and 45 by conduits 47. The compensator functions to indicate in what manner the venturi indications must be changed to compensate for deviations in barometric pressure and temperature relative to the designed constants. The blower control 43 may also be of conventional construction and may preferably be of the type including a calibrated manually operable element for determining the desired blower output in terms of cubic feet of blast gas per minute, for example. Setting of the manually operable element establishes a proportional force which is applied against a force derived from the venturi measuring device 42 which is proportional to the rate of flow of blast gas through the conduit 38. Unbalancing of these forces produces a control signal of the proper characteristic which is transmitted to the motor 32 through lead 48 to increase or decrease the output of the blower and maintain the rate of flow through the conduit 38 equal to the desired rate of flow as determined by the calibrated manually operable element of the blower control 43. In this type of control the loading lines 49 and 50 are usually connected to closed chambers having a common diaphragm wall which moves in opposition to the force established by the manually operable element. With such arrangement a predetermined quantity of blast gas may be constantly maintained automatically with only slight adjustments necessary to compensate the variations in temperature and barometric pressure. Also, the operator may easily determine the quantity of blast gas from a gauge indicating directly the rate of flow of blast gas as determined by the venturi device 42 and the operator may readily change the rate of flow as required by merely adjusting calibrated manually operable element of the blower control 43.

Blast gas blown through the conduit 35 into the furnace comprises a composite stream formed by combining with the stream of atmospheric air flowing through the conduit 38 streams of oxygen or oxygen enriched gas and aqueous fluid such as steam. The oxygen enriching stream is controlled relative to blast gas flowing through the compressor so that the composite stream blown to the furnace comprises a predetermined portion of oxygen which may be varied through fixed limits. Also, aqueous fluid is introduced in such a manner as to establish a constant moisture content in the composite stream, which may be varied, irrespective of the degree of natural moisture in the atmospheric air. The composite stream may be formed so that a constant mass of blast gas may be continually blown into the furnace irrespective of variations in the natural moisture content of the atmospheric air or of changes in the required quantity of moisture and the desired percentage of oxygen enrichment of the blast gas.

A stream of oxygen or oxygen enriched gas may be added to the atmospheric air flowing through the conduit 38 by means of a conduit 59 which may have its discharge end 51 terminated within the conduit 38 on the upstream side of the venturi measuring device 42. The oxygen may be derived from any suitable source 52 which may comprise an air fractionating apparatus capable of producing a large quantity of oxygen of 90%

purity, for example. The oxygen stream from the source 52 is passed through a flow meter 53, a conduit 54 and a control valve 55 before entering the conduit 50. The oxygen stream is of substantially uniform purity and is maintained at substantially constant pressure and temperature so that the amount of oxygen added to the air stream in the conduit 38 and hence the percentage of oxygen enrichment in the composite stream blown to the furnace through the conduit 35 will depend for the most part upon the position of the oxygen control valve 55. A system is provided for regulating the valve 55 to establish and maintain substantially constant predetermined percentages of oxygen enrichment of the composite stream. For this purpose a ratio control 56 is provided which operates responsively to the rate of flow of fluid through the compressor 30 and to the rate of flow of the oxygen stream as determined by the venturi measuring device 42 and the flow meter 53, respectively, to produce a proportional control signal which determines positioning of the oxygen control valve 55 through operation of a suitable transmitter 57. The ratio control 56 may be of any suitable conventional construction and may be similar to the blower control 43 described above in which case a differential pressure actuated diaphragm controlled by the oxygen flow meter would replace the manually operable element and the desired proportioning would be obtained by adjusting spring biasing means in a conventional manner. Specifically, loading line 58 connected to the venturi measuring device 42 and loading line 59 connected to the flow meter 53 communicate with individual chambers spaced by common diaphragms moving in opposition and being adjustably biased to maintain a desired percentage relationship between the oxygen flow and the rate of flow of blast gas. Resultant movement of the diaphragms may be transmitted by means of a mechanical hydraulic or electric medium 60 to the transmitter 57 for controlling the valve 55. With this arrangement the oxygen stream entering the conduit 38 may be accurately controlled so that the composite stream includes a fixed percentage of oxygen as determined by the desired setting of the ratio control 56.

In accordance with the principles of the present invention, moisture necessary to establish a desired moisture content of blast gas blown to the furnace is obtained from a source of low pressure steam, or from a source of low pressure steam and a source of high pressure steam, depending upon the moisture addition required, through a novel arrangement by which the maximum quantity of available low pressure steam is at all times utilized to meet the moisture requirements and the flow of low pressure steam or the flow of high pressure steam is controlled to maintain the total moisture content of blast gas blown to the furnace substantially equal to a predetermined value irrespective of variation of the natural moisture content of the atmospheric air. As shown, steam from a low pressure source 65 is conducted by conduit 66 to a flow meter 67, the purpose of which will be described below. From the flow meter 67, the steam is conducted by conduit 68 to a low pressure steam control valve 69 and thence through conduit 70 which has a discharge end 71 terminated within the conduit 38 at a position which may be upstream of the venturi measuring device 42, as shown, the conduit 70 including a control valve 72. A dew cell 73 is in fluid communication through conduit 74 within the conduit 38 downstream of the discharge end 71 of the conduit 70 for the purpose of measuring the moisture content of blast gas at that point in the system. The output of the dew cell is conducted by lead 75 to a transmitting device 76 coupled to position the valve 69. With this arrangement the control valve 69 is automatically adjusted to at all times permit the maximum flow of steam to the conduit 70 without condensation of water in the conduit 38. The valve 72 is controlled by a transmitting device 77 connected through lead 78, switch 79 and lead

80 to a moisture control device 81. The moisture control device is fed with a control signal from a dew cell 82 through a lead 83 and the dew cell is connected to within the conduit 34 downstream of the discharge of the compressor 30 through a conduit 84. The dew cell 82 (and also the dew cell 73) may be of conventional construction and may comprise a humidity sensitive cell that may be adjusted to produce an output signal proportional to the absolute humidity of blast gas flowing through the conduit 34, the output signal being fed through lead 83 to the moisture control device 81. The moisture control device may also be of conventional construction and may be similar to the blower control 43 described above. With this type of control the signal supplied by the dew cell, which is proportional to the moisture content of the blast gas, is converted into a force which is balanced against a force proportional to a predetermined or desired moisture content value established by the position of a calibrated manually operable element. An error signal is generated responsively to any difference between the forces and the error signal is transmitted by lead 80, switch 79 and lead 78 to the transmitter 77 for adjusting the position of the valve 72. With this arrangement the moisture control 81 is adjusted by proper setting of its manually operable element to maintain a desired moisture content, such as 10 grains per cubic foot of blast gas, for example. Thereupon, assuming the natural moisture in the air entering conduit 38 produces 4 grains of moisture per cubic foot of blast gas, the valve 72 would be automatically adjusted to provide a flow of steam sufficient to add a moisture content of 6 grains per cubic foot to the blast gas. Should the natural moisture content of the air change under these circumstances, the valve 72 would be automatically moved to the required position to maintain a supply of aqueous fluid to the blast gas equal to the difference between the desired moisture content and the natural moisture in the atmospheric air.

A source of high pressure steam 90 is provided together with an arrangement for adding high pressure steam to the blast gas when the desired moisture content is greater than that that may be maintained from the source of low pressure steam. Stream from the high pressure source is conducted through conduit 91, flow meter 92, conduit 93, control valve 94 and into conduit 95 which has a discharge end 96 terminated within the conduit 34 on the discharge side of the compressor 30. The valve 94 is controlled by a transmitting device 97 which operates in accordance with a signal from the moisture control 81 conducted thereto through lead 80, switch 79 and lead 98. The switch 79 may occupy a first position in which the lead 80 is connected only to the lead 78 or a second position in which the lead 80 is connected only to the lead 98, and the switch 79 is moved to the first position or the second position by a transmitting device 99. The transmitting device 99 is connected to switches 100 and 101 through leads 102 and 103, respectively, and the switch 100 is operatively connected to the transmitting device 77 of the low pressure steam supply while the switch 101 is operatively connected to the transmitting device 97 of the high pressure steam supply. When the valve 72 is in closed position the switch 100 is positioned to effect energization of the transmitting device 99 and move the switch 79 to its first position in which the lead 80 is connected only to the lead 78. However, when the valve 72 is moved to full open position, the switch 100 operates to cause the transmitting device 99 to move the switch 79 to its second position by which lead 80 is connected only to the lead 98. Also, the switch 101 is designed to operate when the valve 94 is moved to closed position to effect energization of the transmitting device 99 for moving the switch 79 to its first position and establish a connection between leads 80 and 78. The switch 100 also operates responsively to the flow meter 67 through lead

104 and to a pressure measuring device 105 connected to the conduit 66 through a conduit 106. Should the rate of flow of the low pressure stream drop below required limits, the switch 100 operates to effect movement of the switch 79 to its second position and connect leads 80 and 98 irrespective of the position of valve 72. In operation, the blower control 43 is set to establish the desired rate of flow of blast gas through the compressor 30, the ratio control 56 is adjusted to establish 10 a desired percentage of oxygen enrichment and the moisture control 81 is set to establish the desired quantity of moisture in the blast gas blown to the furnace. When the desired moisture content of the blast gas is less than the maximum moisture that may be added to the blast gas 15 through the introduction of low pressure steam, as determined by the dew cell 73 and the control valve 69, the moisture control 81 is connected through lead 80, switch 79 and lead 78 to the transmitting device 77 to maintain the moisture content of blast gas substantially equal to 20 the desired value by controlling the valve 72. However, when the desired moisture content is greater than the maximum moisture that may be provided by the low pressure steam source, the valve 72 will move to its full open position at which time switch 100 operates to energize the transmitting device 99 and move switch 79 to 25 its second position and thereby place the high pressure steam control valve 94 under control of the moisture control 81. The quantity of high pressure steam entering the blast gas on the discharge side of the compressor 30 through conduit 95 is substantially equal to the difference 30 between the moisture indicated by the dew cell 73, that is, the natural moisture plus the moisture provided by the low pressure steam source, and the desired moisture content. The quantity of high pressure steam entering the 35 blast gas is indicated by the meter 92 and the rate of flow of blast gas to the furnace may be easily calculated. Variations in the natural moisture content of the air are automatically compensated for by controlling the flow of low pressure or high pressure steam entering the system 40 through operation of valves 72 or 94.

With this arrangement it is possible to introduce into the blast gas any desired quantity of moisture, which may be maintained substantially constant irrespective of variations in the natural moisture content of the air, while at 45 all times utilizing the maximum possible quantity of available low pressure steam. Since in most blast furnace installations an ample quantity of low pressure steam is obtainable without expense, while providing high pressure steam adds to the cost of the product, this feature of the 50 invention results in substantial savings in view of the large quantities of moisture blown into the furnace during each twenty-four hours of operation.

In the embodiment of the invention shown in Figure 2 of the drawings the oxygen stream and the stream of low 55 pressure steam are introduced into the blast gas in the conduit 38 on the suction side of the compressor and the high pressure steam is introduced through conduit 95 into conduit 34 on the discharge side of the compressor while the venturi measuring device 42 is positioned in the conduit 34 on the discharge side of the compressor downstream of the high pressure steam conduit 95 and upstream of the conduit 84 leading to the dew cell 82. This arrangement operates in a manner similar to the arrangement shown in Figure 1 with the exception that the total 60 blast gas blown to the furnace flows through the venturi measuring device 42 and the quantity of blast gas entering the furnace may be established by the blower control 43. This arrangement eliminates the necessity of utilizing a high pressure steam flow meter, such as the flow meter 92 of Figure 1 in order to ascertain the total blast entering 65 the furnace. Of course, a flow meter such as the meter 92 may be included in the conduit 95 to indicate the quantity of high pressure steam entering the blast gas.

In the embodiment of the invention shown in Figure 3 70 of the drawings, steam from the low pressure source 65

is conducted by conduit 110 to the low pressure steam control valve 72 and then fed to conduit 111 having a discharge end 112 terminating within the conduit 38 on the suction side of the compressor 30. The moisture control 81 is connected by lead 113 to the transmitting device 77 for the valve 72, while the moisture control is also connected through lead 83 to the dew cell 82 having a connection by conduit 84 to the conduit 34 on the discharge side of the compressor 30 in a manner similar to the arrangements shown in Figures 1 and 2. Steam from the high pressure source 90 is conducted through conduit 91 to flow meter 92 and from the flow meter the steam is passed by way of conduit 114, control valve 115, and conduit 116 to the conduit 34 on the discharge side of the compressor upstream of the dew cell conduit 84. The means for controlling the compressor 30 and for establishing the percentage of oxygen enrichment are similar to the arrangements shown in Figure 1. In Figure 3 there is also illustrated one of a plurality of stoves 120 having an inlet conduit 121 connected to the conduit 34 and an outlet conduit 122 connected to the conduit 35 with a by-pass 123 having a control valve 124 connected between the conduits 121 and 122.

In operation of the arrangement shown in Figure 3, the moisture control 81 functions to position the low pressure steam control valve 72 and thereby control the quantity of low pressure steam introduced into the blast gas upstream of the compressor and maintain a substantially constant quantity of moisture in the blast gas blown to the furnace, as determined by the moisture control 81, irrespective of variations of natural moisture content of atmospheric air entering the conduit 38. When high quantities of moisture in excess of the total moisture that may be obtained by adding low pressure steam to the suction side of the compressor are required in the blast gas, valve 115 is manually adjusted so that a fixed quantity of steam from the high pressure source is fed through conduit 116 into the blast gas on the discharge side of the compressor. For example, it is assumed that 20 grains of moisture per cubic foot of blast gas is required, that the natural moisture content of the atmospheric air is 6 grains per cubic foot and that the temperature conditions of the atmospheric air are such that a maximum of 10 grains per cubic foot of blast gas may be maintained on the suction side of the compressor through the addition of low pressure steam, the high pressure steam control valve 115 would be manually adjusted to feed 10 grains of moisture per cubic foot of blast gas into the conduit 34, the quantity of moisture being indicated on the meter 92. The moisture control 81, being set to maintain a moisture content of 20 grains per cubic foot of blast gas then functions to control the valve 72 through the transmitting device 77 and supply a quantity of low pressure steam equal to 5 grains of moisture per cubic foot of blast gas. Any variations in the natural moisture content of the air would cause an increase or decrease in the flow of low pressure steam to maintain the total moisture entering the furnace at the desired quantity of 20 grains per cubic foot of blast gas. Means may be provided for operating the high pressure steam control valve 115 responsively to the blower control 43 so that the flow of high pressure steam to the blast gas is materially decreased or shut off at times when the wind blown to the furnace is severely reduced such as during tapping operations, for example.

There is thus provided by the present invention novel apparatus for controlling the composition of blast gas such as for establishing and maintaining the percent of oxygen enrichment and the quantity of moisture in blast gas substantially in accordance with predetermined requirements. The arrangement is such that a wide range of moisture content may be maintained in blast gas blown to the furnace, such as from about 3 grains to 80 or more grains per cubic foot of blast gas, by the introduction of low pressure steam on the suction side of the com-

pressor and high pressure steam on the discharge side of the compressor in a novel manner that insures utilization of the maximum quantity of low pressure steam in establishing the desired moisture content.

Although several embodiments of the invention have been disclosed and described herein, it is to be expressly understood that various changes and substitutions may be made therein without departing from the spirit of the invention as well understood by those skilled in the art. For example, in the arrangement shown in Figure 3 of the drawings, the venturi measuring device 42 may be located in the conduit 34 on the discharge side of the compressor 30 in the manner shown in Figure 2 of the drawings, if desired. Reference therefore will be had to the appended claims for a definition of the limits of the invention.

What is claimed is:

1. In a blast furnace installation including a blast furnace having tuyere means through which blast gas is discharged into the furnace, means including compressor means for blowing blast gas to the tuyere means, measuring means for measuring the rate of flow of blast gas through the compressor means, control means operative responsively to the measuring means for controlling the compressor means, means including first conduit means for introducing low pressure water vapor into blast gas on the suction side of the compressor means, means including second conduit means for introducing relatively high pressure water vapor into blast gas on the discharge side of the compressor means, moisture measuring means for measuring the moisture content of blast gas blown to the tuyere means, and moisture control means operative responsively to the moisture measuring means for controlling the flow of water vapor in the first conduit means.

2. In a blast furnace installation including a blast furnace having tuyere means through which blast gas is discharged into the furnace, means including compressor means for blowing blast gas to the tuyere means, the blast gas including atmospheric air, measuring means for measuring the rate of flow of blast gas through the compressor means, control means operative responsively to the measuring means for controlling the compressor means, means including first conduit means for introducing low pressure water vapor into blast gas on the suction side of the compressor means, means including second conduit means for introducing relatively high pressure water vapor into blast gas on the discharge side of the compressor means, moisture measuring means for measuring the moisture content of blast gas blown to the tuyere means, moisture control means connected to the moisture measuring means and including comparing means for comparing the moisture content of blast gas blown to the tuyere means and a predetermined moisture content, and means for controlling the rate of flow of water vapor in the first conduit means responsively to the comparing means to maintain a moisture content in the blast gas substantially corresponding to the predetermined moisture content irrespective of variations of the natural moisture content of the atmospheric air.

3. In a blast furnace installation including a blast furnace having tuyere means through which blast gas is discharged into the furnace, means including compressor means for blowing blast gas to the tuyere means, measuring means for measuring the rate of flow of blast gas through the compressor means, control means operative responsively to the measuring means for controlling the compressor means, means including first conduit means for introducing low pressure water vapor into blast gas on the suction side of the compressor means, means including second conduit means for introducing a substantially constant quantity of relatively high pressure water vapor into blast gas on the discharge side of the compressor means, moisture measuring means for measuring the moisture content of blast gas blown to the tuyere means, and moisture control means operative responsively

to the moisture measuring means for controlling the flow of water vapor in the first conduit means.

4. In a blast furnace installation including a blast furnace having tuyere means through which blast gas is discharged into the furnace, means including compressor means for blowing blast gas to the tuyere means, the blast gas including atmospheric air, measuring means for measuring the rate of flow of blast gas through the compressor means, control means operative responsively to the measuring means for controlling the compressor means, means including first conduit means for introducing low-pressure water vapor into blast gas on the suction side of the compressor means, means including second conduit means for introducing a substantially constant quantity of relatively high pressure water vapor into blast gas on the discharge side of the compressor means, moisture measuring means for measuring the moisture content of blast gas blown to the tuyere means, moisture control means connected to the moisture measuring means and including comparing means for comparing the moisture content of blast gas blown to the tuyere means and a predetermined moisture content, and means for controlling the rate of flow of water vapor in the first conduit means responsively to the comparing means to maintain a moisture content in the blast gas substantially corresponding to the predetermined moisture content irrespective of variations of the natural moisture content of the atmospheric air.

5. In a blast furnace installation including a blast furnace having tuyere means through which blast gas is discharged into the furnace, means including compressor means for blowing blast gas to the tuyere means, measuring means for measuring the rate of flow of blast gas through the compressor means, control means operative responsively to the measuring means for controlling the compressor means, means including first conduit means for introducing low pressure water vapor into blast gas on the suction side of the compressor means, means including second conduit means for introducing relatively high pressure water vapor into blast gas on the discharge side of the compressor means, moisture measuring means for measuring the moisture content of blast gas blown to the tuyere means, and means responsive to the measuring means for controlling flow of water vapor through the first conduit means and through the second conduit means.

6. In a blast furnace installation including a blast furnace having tuyere means through which blast gas is discharged into the furnace, means including compressor means for blowing blast gas to the tuyere means, the blast gas including atmospheric air, measuring means for measuring the rate of flow of blast gas through the compressor means, control means operative responsively to the measuring means for controlling the compressor means, means including first conduit means for introducing low-pressure water vapor into blast gas on the suction side of the compressor means, means including second conduit means for introducing relatively high pressure water vapor into blast gas on the discharge side of the compressor means, moisture measuring means for measuring the moisture content of blast gas blown to the tuyere means, moisture control means connected to the moisture measuring means and including comparing means for comparing the moisture content of blast gas blown to the tuyere means and a predetermined moisture content, and means for controlling the flow of water vapor in the first conduit means and in the second conduit means responsively to the comparing means to maintain a moisture content in the blast gas substantially corresponding to the predetermined moisture content irrespective of variations of the natural moisture content of the atmospheric air.

7. In a blast furnace installation including a blast furnace having tuyere means through which blast gas is discharged into the furnace, means including compres-

sor means for blowing blast gas into the tuyere means, measuring means for measuring the rate of flow of blast gas through the compressor means, control means operative responsively to the measuring means for controlling

- 5 the compressor means, means for introducing atmospheric air to the suction side of the compressor means, means including first conduit means for introducing water vapor into blast gas on the suction side of the compressor means, means for controlling the flow of water vapor in
- 10 the first conduit means to limit the total moisture of blast gas on the suction side of the compressor means below a critical level that would result in condensation of water vapor, means including second conduit means for introducing water vapor into blast gas on the discharge side of the compressor means, and means for controlling the flow of water vapor through the first conduit means and the second conduit means responsively to the moisture content of blast gas blown to the tuyere means, the last-named means including means for controlling the flow of water vapor through the first conduit means responsively to variations of moisture content of blast gas blown to the tuyere means less than said level, and means for controlling the flow of water vapor through the second conduit means responsively to variations of moisture content of blast gas blown to the tuyere means greater than said level.

8. In a blast furnace installation including a blast furnace having tuyere means through which blast gas is discharged into the furnace, means including compressor

- 30 means for blowing blast gas to the tuyere means, measuring means for measuring the rate of flow of blast gas through the compressor means, control means operative responsively to the measuring means for controlling the compressor means, means for adding oxygen rich gas to the blast gas, means for measuring the flow of oxygen rich gas, means for comparing the flow of oxygen rich gas and the rate of flow of blast gas through the compressor means to determine the percentage of oxygen in blast gas blown to the tuyere means, means including first conduit means for introducing low pressure water vapor into blast gas on the discharge side of the compressor means, moisture measuring
- 35 means for measuring the moisture content of blast gas blown to the tuyere means, and moisture control means operative responsively to the moisture measuring means for controlling the flow of water vapor in the first conduit means.
- 40

9. In a blast furnace installation including a blast furnace having tuyere means through which blast gas is discharged into the furnace, means including compressor means for blowing blast gas to the tuyere means, the blast gas including atmospheric air, measuring means for

- 55 measuring the rate of flow of blast gas through the compressor means, control means operative responsively to the measuring means for controlling the compressor means, means for adding oxygen rich gas to the blast gas, means for measuring the flow of oxygen rich gas, means for comparing the flow of oxygen rich gas and the rate of flow of blast gas through the compressor means to determine the percentage of oxygen in blast gas blown to the tuyere means, means including first conduit means for introducing low pressure water vapor into blast gas on the suction side of the compressor means, means including second conduit means for introducing relatively high pressure water vapor into blast gas on the discharge side of the compressor means, moisture measuring means for measuring the moisture content of blast gas blown to the tuyere means, moisture control means including comparing means for comparing the moisture content of blast gas blown to the tuyere means and a predetermined moisture content, and means for controlling the rate of flow of water vapor in the first conduit means responsively to the comparing means to maintain a moisture content

11

in the blast gas substantially corresponding to the predetermined moisture content irrespective of variations of the natural moisture content of the atmospheric air.

10. In a blast furnace installation including a blast furnace having tuyere means through which blast gas is discharged into the furnace, means including compressor means for blowing blast gas to the tuyere means, measuring means for measuring the rate of flow of blast gas through the compressor means, control means operative responsive to the measuring means for controlling the compressor means, means for adding oxygen rich gas to the blast gas, means for measuring the flow of oxygen rich gas, means for comparing the flow of oxygen rich gas and the rate of flow of blast gas through the compressor means to determine the percentage of oxygen in blast gas blown to the tuyere means, means including first conduit means for introducing low pressure water vapor into blast gas on the suction side of the compressor means, means including second conduit means for introducing a substantially constant quantity of relatively high pressure water vapor into blast gas on the discharge side of the compressor means, moisture measuring means for measuring the moisture content of blast gas blown to the tuyere means, and moisture control means operative responsive to the moisture measuring means for controlling the flow of water vapor in the first conduit means.

11. In a blast furnace installation including a blast furnace having tuyere means through which blast gas is discharged into the furnace, means including compressor means for blowing blast gas to the tuyere means, measuring means for measuring the rate of flow of blast gas through the compressor means, control means operative responsive to the measuring means for controlling the compressor means, means including first conduit means for introducing low pressure water vapor into blast gas on the suction side of the compressor means, means including second conduit means for introducing relatively high pressure water vapor into blast gas on the discharge side of the compressor means, moisture measuring means for measuring the moisture content of blast gas blown to the tuyere means, first control means for controlling the flow of low pressure water vapor through the first conduit means, second control means for controlling the flow of relatively high pressure water vapor through the second conduit means, and means for connecting the moisture measuring means to the first control means when the moisture content of blast gas blown to the tuyere means is below a predetermined level and for connecting the moisture measuring means to the second control means when the moisture content of blast gas blown to the tuyere means is above the predetermined level.

12. In a blast furnace installation as defined in claim 11, with the means for connecting the moisture measuring means to the first control means and for connecting the moisture measuring means to the second control means

12

including means operable responsive to the first control means and the second control means.

13. In a blast furnace installation as defined in claim 11, means independent of the first control means operable to maintain the moisture content of blast gas on the suction side of the compressor means below a critical value that would result in condensation of water vapor, and means operative responsive to the last-named means for effecting control of the second control means responsive to the measuring means.

14. In a blast furnace installation including a blast furnace having tuyere means through which blast gas is discharged into the furnace, means including compressor means for blowing blast gas to the tuyere means, measuring means for measuring the rate of flow of blast gas through the compressor means, control means operative responsive to the measuring means for controlling the compressor means, means for introducing atmospheric air to the suction side of the compressor means, means including first conduit means for introducing low pressure water vapor into blast gas on the suction side of the compressor means, means including second conduit means for introducing relatively high pressure water vapor into blast gas on the discharge side of the compressor means, moisture measuring means for measuring the moisture content of blast gas blown to the tuyere means, first control means for controlling the flow of low pressure water vapor through the first conduit means, second control means for controlling the flow of high pressure water vapor through the second conduit means, switch means connected to the moisture measuring means and operable in one position to connect the moisture measuring means to the first control means and operable in a second position to connect the moisture measuring means to the second control means, means for operating the switch means to the first and second positions, means operative responsive to a predetermined position in the first control means for operating the switch means to the second position and means operative responsive to a predetermined position in the second control means for operating the switch means to the first position.

15. In a blast furnace installation as defined in claim 14, means for measuring the moisture content of blast gas on the suction side of the compressor means and for controlling the flow of low pressure steam to the first conduit means independently of the first control means, means operable responsive to the rate of flow of the low pressure steam in the first conduit means for moving the switch means to the second position.
